Walter Gropius, Design for a Clock Front

4496

PATENTED Nov 29 1870

August Weizsäcker
Charles Tischbirek

Charles Parker

United States Patent Office.

NICHOLAS MULLER, OF NEW YORK, N. Y.

Design No. 4,496, dated November 29, 1870.

DESIGN FOR A CLOCK-FRONT.

The Schedule referred to in these Letters Patent and making part of the same.

To all whom it may concern:

Be it known that I, NICHOLAS MÜLLER, of the city, county, and State of New York, have invented a new and ornamental Design for a Clock-Front; and I do hereby declare that the following is a full, clear, and exact description thereof, which will enable those skilled in the art to make and use the same, reference being had to the accompanying photograph forming part of this specification, in which the design is represented by a front view.

This invention relates to a design for a clock-front.

For convenience in description it may be divided into two parts by the line of division *l l*,
a a being the upper, and
b b, the lower part.

In the part *b b* is represented a fight between a dog and a cock, forming the main feature of the design.

The dog's head and fore legs nearly touch the ground. He is crouching down, with open jaw, awaiting the attack. The cock is also in a fighting posture, ready to spring at him.

Between the dog and cock is a circular frame containing a medallion head of a cat as a spectator to the

fray. This frame is detachable, and closes the pendulum-hole.

In the center of the bottom of this part *b b* is a large arabesque, forming part of the bottom edge.

The back-ground of the part *b b* is embellished by rich ornaments and foliage.

The part *a a* is, for the most part, occupied by the dial *d*.

On each side of the dial *d*, touching the line of division *l l*, are three small ornamental squares.

The portion above the dial *d* is formed in the center by an ornamental scroll, with an arabesque on both sides, the whole adding greatly to the finish of the design.

What I claim as my invention, and desire to secure by Letters Patent, is—

The whole design for a clock-front, as herein shown and described.

Signed this 5th day of November, 1870.

NICHOLAS MÜLLER.

Witnesses:

CHARLES KITSCHELT,
AUGUST WIEDERKEHR.
